UNITED STATES PATENT OFFICE.

ROBERT ROCHESTER, OF DAYTON, OHIO, ASSIGNOR TO THE BARNEY & SMITH CAR COMPANY, OF SAME PLACE.

CAR-SEAT.

SPECIFICATION forming part of Letters Patent No. 595,415, dated December 14, 1897.

Application filed November 2, 1896. Serial No. 610,829. (No model.)

To all whom it may concern:

Be it known that I, ROBERT ROCHESTER, a citizen of the United States, residing at Dayton, in the county of Montgomery and State 5 of Ohio, have invented certain new and useful Improvements in Car-Seats, of which the following is a specification, reference being had therein to the accompanying drawings.

My invention has reference to car-seats of 10 the class in which the back is reversible and in which the cushion is shifted back and forth by the movement of the back in reversing, and it is designed more particularly as an improvement upon the seat shown and described 15 in United States Letters Patent No. 491,761.

The objects of my invention are, first, to simplify the construction of the seat shown, described, and claimed in said patent; second, to obtain more clearance under the seat- 20 rail to better accommodate a system of heating-pipes; third, to reduce the travel or movement of the cushion whereby more clearance room is obtained between the front edge of 25 one cushion and the back of the seat in front, also greater clearance room between the front edges of two cushions when seats are set facing each other; fourth, to detachably connect the rocker with the seat-frame whereby, when the cushion is removed for cleaning or 30 other purposes, a number of cushions can be piled up on one another without danger of mutilating the upholstery; fifth, to provide more simple and efficient means for attaching the lever-arms to the shafts, and, sixth, to otherwise reduce the cost of construction of 35 such seats, the manner in which I accomplish these objects being hereinafter fully described, and shown in the accompanying drawings, in which—

40 Figure 1 is a perspective view of a car-seat embodying my improvements and in which the seat end, the cushion, and other parts are broken away to show the construction of the operating mechanism; Fig. 2, a vertical cross- 45 section through the center of the seat with the cushion-frame removed, the reversed normal position of the back being represented by dotted lines; Fig. 3, a broken plan view of the wall-end plate and operating mechan- 50 ism; Fig. 4, a perspective view of the bottom side of the cushion-frame; Fig. 5, a per-

spective view of the rocker; Fig. 6, a perspective view of the end plate attachable to the wall of the car; Fig. 7, a perspective view from the inside of the seat end adjacent to the 55 aisle of the car detached from the seat; Fig. 8, a like view of one of the back arms with connecting-levers and cams attached.

Similar numerals of reference indicate corresponding parts in all the figures of the draw- 60 ings.

The seat-frame is composed of two end plates 1 2, the plate 2 being preferably formed integral with a stand 3, and these end plates are united by rails 4 5, secured at their ends 65 in sockets 6 on said plates. The plate 1 is secured to the wall 7 of the car, and the stand 3 is secured to the car-floor. A wood seat end 8 is screwed to plate 2 and may be of any of the well-known forms, or it may be made of 70 metal and formed integral with the plate 2 and stand 3. The plates 1 and 2 are provided with journal-bearings 9, in which the ends of rotatable shafts 10 11 are mounted, on which and near the ends thereof in proximity to the inside 75 of the end plates are mounted substantially parallel lever-arms 12 13, arranged in pairs and about equal in length. These arms are each provided with a hub 14, having a cam 15 and a projecting lug 16. These hubs are preferably 80 cast on a core and with a longitudinal slot 17, extending across the edges of the lever-arms, the object of which is to avoid the necessity of boring the hubs to fit the shafts, which, as a matter of economy, are made of ordinary gas- 85 pipe, which varies more or less in size, and by casting the hub with a slot, as described, and using a core of slightly less diameter than that of the pipe as it usually runs the hub, which by preference is made of malleable iron, can 90 be driven onto the pipe, the slot permitting it to spread or enlarge its diameter to suit the pipe, and thus a tight fit is obtained without the employment of machine labor and in a very inexpensive manner. When the hub is 95 driven to place on the shaft, it may be riveted or otherwise additionally secured. The top side of rails 4 5 are inclined toward the center of the seat and carry at each end a rocker 18, having correspondingly-inclined surfaces 100 19, upwardly-projecting pins 20, ears 21, and an opening 22, formed by a reduced portion

23, and arms 24 25, through which opening the hubs 14 rotate by the movement of the seat-back 26, which is provided with arms 27 and to which the lever-arms are pivoted at 5 28. The rockers are held in line by guides 29, formed on the sockets 6, and the projecting lugs 16, formed on the hubs 14, which lugs are so arranged as that one of them will at all 10 times be in proper relation with each rocker to prevent lateral displacement of the same.

The function of the arms 24 25 is to prevent the upward displacement of the rockers while the cushion-frame 30 is being removed, and the latter being supported on the rockers is 15 held in position by the projecting pins 20, which engage holes 31 in the bottom of the cushion-frame, by which arrangement the latter can be easily and quickly removed and replaced by one man, while in the seat of the 20 patent to which I have referred two men are required to remove or replace the cushion, owing to the difficulty experienced in adjusting the rockers (which in said patent are described as "runners") to their proper positions 25 in consequence of their being secured to and removable with the cushion-frame; and as in cleaning cars it is the usual custom to remove all the seat-cushions and pile them up in a convenient place where they can be 30 scrubbed or otherwise renovated it is essential that there be no projections of any kind about the cushion-frames to interfere with piling them compactly or to cause mutilation of the upholstery, and it will be observed that by 35 detachably mounting the cushion-frame to the rockers in the above-described manner I obviate all danger of injuring the upholstery by piling the frames one upon another.

To the inner edges of the rails 4 5 and at 40 some distance from the wall end of the seat are suspended hangers 32 33, which support the ends of foot-rests 34 35, the opposite ends of which are supported by the stand 3 in the usual manner, the object in locating the hangers 32 33 away from the wall being to provide 45 sufficient space for a system of heating-pipes to extend longitudinally of the car against the wall thereof, and as it is desirable to have as much space as possible under the center of 50 the seats to accommodate lateral pipes, which are frequently extended from the longitudinal heating system, I have reduced the length of the cams and all other parts likely to interfere with such pipes to a minimum and 55 have also thereby reduced the forward-and-backward movement of the cushion-frame caused by the shifting of the seat-back, thus gaining room between the seats in whichever position they may be set, still retaining the 60 necessary relative position of the cushion and back to be comfortable for the occupant of the seat without increasing the space required in which to reverse the back.

When the seat-back is in either of its two 65 normal positions, as shown in Fig. 1 and by dotted lines in Fig. 2, the ends of the rockers are at rest on the inclined surfaces of the

rails 4 5, and in order that the shifting movement of the back and cushion may be the more clearly understood I will now describe 70 it in reference to Fig. 2 of the drawings. When the back is shifted from the position shown in full lines to the one shown in dotted lines, or vice versa, the movement of the lever-arms 12 13 will cause a partial rotation of 75 the two shafts 10 11, thereby oscillating the cams 15 and projecting lugs 16, and when the back is in the position shown by full lines the cams attached to the rear shaft 10 impinge against their coöperating ears 21 of the rockers, and as they are rotated by the shifting of 80 the back the two rockers will be moved down the incline of rail 4 and will ride upward over the inclined surface of rail 5 in the opposite direction to that of the movement of 85 the back, and vice versa, and thus cause the cushion to extend beyond the seat-rail on the front side and simultaneously ride upward at the same side into an inclined position, tending to add greater comfort to the occupant. 90 The movement of the back is limited by the sockets 6, which, in addition to the function already ascribed to them, act as stops for the lever-arms 12 13 to strike against when the back is shifted from one of its normal positions to the other and by which further downward movement of the back is arrested. Various other forms of stops may be employed for the purpose, but I prefer the one just described, on account of its simplicity 95 and economical advantages.

In the foregoing I have described only such detail of operation and construction as I have deemed necessary to clearly explain my invention in connection with the seat of said 105 Patent No. 491,761; but it is obvious that my improvements are applicable to seats differing in structural detail from the one described and claimed in said patent, and therefore I do not wish to limit my invention to such 110 exact construction.

Having thus described my invention, I claim—

1. In a car-seat of the class described, the combination of a frame, consisting of a pair of 115 end plates having sockets formed thereon, and a pair of rails, the ends of which are held in said sockets, a pair of shiftable rockers, a detachable cushion-frame carried by said rockers, guides formed on said sockets to retain 120 said rockers in line, a shiftable back, mechanism connecting said back with said rockers, whereby the latter is shiftable horizontally of the seat by the movement of the former, and arms formed on said rockers to 125 prevent their displacement when the cushion-frame is removed, substantially as set forth.

2. In a car-seat of the class described, the combination of a frame, consisting of a pair of end plates having sockets formed thereon; 130 and a pair of rails, the ends of which are held in said sockets, a pair of shiftable rockers, a detachable cushion-frame carried by said rockers, guides formed on said sockets to retain

- 5 said rockers in line, a shiftable back, mechanism connecting said back with said rockers, whereby the latter are shiftable horizontally of the seat by the movement of the former, arms formed on said rockers to prevent their displacement when the cushion-frame is removed, pins formed on said rockers and projecting upwardly therefrom, and holes in the under side of said cushion-frame 10 to engage said pins, substantially as set forth.
3. In a car-seat of the class described, the combination of a frame, consisting of a pair of end plates having sockets formed thereon; and a pair of rails, the ends of which are held 15 in said sockets, a seat-back, a pair of lever-arms, substantially equal in length, pivotally connected, at or near their upper extremities to each end of the back at or near the bottom thereof, and having their lower extremities 20 pivoted to said end plates near the center thereof, the said upper pivotal connections being arranged at an angle to the plane of the back, a pair of shiftable rockers operated by the movement of the back, guides located 25 on said sockets for retaining the said rockers in line, arms formed on said rockers to prevent their displacement, and stops for limiting the movement of said lever-arms, substantially as described.
- 30 4. In a car-seat of the class described, the combination with a back, and a frame consisting of a pair of end plates having sockets formed thereon; and a pair of rails, the ends of which are held in said sockets, of a pair of lever-arms substantially equal in length, pivotally connected near their upper extremities to each end of the back at or near the bottom thereof, the said upper pivotal connections being arranged at an angle to the plane of 35 the back, a pair of shafts pivotally mounted in the said end plates and to the ends of which the lower extremities of the said lever-arms are attached, whereby the said shafts are rotated by the movement of the back, a pair of 40 shiftable rockers, and a cushion-frame carried by the said rockers, guides located on the said sockets for retaining the said rockers in line, arms formed on the said rockers for preventing their displacement, and means 45 for operating the said rockers by the movement of the back, substantially as described.
5. In a car-seat of the class described, the combination of a back, and a frame consisting of a pair of end plates having sockets formed 50 thereon; and a pair of rails whose ends are held in said sockets, of a pair of lever-arms substantially equal in length and arranged substantially parallel with each other, the said lever-arms being pivotally connected, at or near their upper extremities, to each end of the back, at or near the bottom thereof, and to the said end plates at or 55 near their lower extremities, each of said lever-arms having a hub projecting at an angle thereto, and a cam projecting at an angle to

said hub, a pair of rockers, a detachable cushion-frame, holes in the under side of said cushion-frame, pins projecting upwardly from said rockers and adapted to engage said holes, the said rockers being shiftable horizontally 70 of the seat through the medium of ears attached thereto or formed integral therewith, and projecting from the inner sides of said rockers at an angle thereto, and which said cams impinge said ears, whereby the shifting 75 of the back imparts a rocking movement to the said rockers, thereby causing the said cushion-frame to automatically move with the back, guides located on the said sockets for retaining the said rockers in line, arms 80 attached to, or formed integral with the said rockers for preventing their displacement when the cushion-frame is removed, and a stop for limiting the downward movement of the back, substantially as set forth. 85

6. In a car-seat of the class described, the combination of a shiftable back, and a frame consisting of a pair of end plates having sockets formed thereon; and a pair of inclined-surfaced rails, the ends of which are held in 90 said sockets, of a pair of rockers having inclined surfaces corresponding with those of said rails, pins projecting upwardly from said rockers, a cushion-frame carried by the said rockers and having holes adapted to engage 95 the said pins, the said rockers being automatically shifted to and fro, on, and up and down the inclined surfaces of the said rails by suitable mechanism connecting the said rockers with the said back, guides located on 100 the said sockets for retaining the said rockers in line, and arms attached to or formed integral with the said rockers, whereby displacement of the latter, when the cushion-frame is removed, is prevented, substantially as set 105 forth.

7. In a car-seat of the class described, a shiftable back, and a frame consisting of a pair of end plates having sockets formed thereon; and a pair of rails, the ends of which 110 are held in said sockets, a plurality of lever-arms pivotally connecting the back with the frame, each of the said lever-arms having a projecting hub formed on the inner side thereof at or near their lower ends and each hub 115 being provided with a cam, a pair of shafts rotatably mounted in said frame and passing through said hubs and lever-arms and to which the said shafts are secured, the said hubs and lever-arms being split to form a 120 spring fit around the shafts, in combination with a pair of rockers provided with ears which coöperate with the said cams and shift the rockers by the movement of the back 125 through the medium of the lever-arms, substantially as set forth.

ROBERT ROCHESTER.
